W. H. GLENN

MOP

Filed Oct. 7, 1922

Inventor

WILLIAM H. GLENN

Ch. Parker
Attorney

UNITED STATES PATENT OFFICE.

WILLIAM H. GLENN, OF QUINCY, ILLINOIS.

MOP.

Application filed October 7, 1922. Serial No. 593,054.

To all whom it may concern:

Be it known that I, WILLIAM H. GLENN, a citizen of the United States, residing at Quincy, in the county of Adams and State 5 of Illinois, have invented certain new and useful Improvements in Mops, of which the following is a specification.

This invention relates to mops, and is an improvement over the construction shown in 10 my copending application filed December 27, 1921, Serial No. 525,089.

An object of the invention is the provision of a mop which may be readily attached to a broom and detached therefrom.

15 In the present invention, I provide a body portion adapted to fit around a broom head, the body portion being provided with mop elements on one side and an extension secured to a portion of the lower edge of the body 20 portion, the extension being adapted to pass under the broom and extend partially up the other side, said extension being provided with mop elements on its outer face.

A further object of the present invention 25 is the provision of improved means for securing the free end of the extension in place.

In the accompanying drawings, I have shown one embodiment of the invention. In this showing:

30 Figure 1 is a perspective view of a broom showing the device applied thereto,

Figure 2 is a perspective view of the mop removed,

Figure 3 is a side elevation, and,

35 Figure 4 is a central vertical sectional view.

Referring to the drawings, the reference numeral 1 designates a broom of ordinary construction having a handle 2. The mop 40 forming the subject matter of the present invention consists of a tubular casing 3, adapted to fit over a broom. The lower edge of the casing is provided with an extension 4 which passes under the broom, as at 5, and 45 is then arranged on the opposite side of the casing. Tie ribbons 6 are secured to the upper edge of the casing on opposite sides and adapted to be tied around the handle as shown in Figure 1 of the drawings. Mop 50 elements 8 are secured to the side of the casing to which the extension is secured. As shown, the mop elements consist of strings arranged vertically of the casing and at-

tached thereto by means of parallel strips 9, 55 stitched to the casing. The extension is provided with similar mop elements 10, which are adapted to be arranged beneath the broom and on the opposite side, when the extension is in position. The free edge of the extension is provided with tie strings 11. 60 The adjacent side of the casing is provided with similar strings 12 to which the strings 11 are tied, forming bows 13 to retain the extension in position.

In attaching the device to a broom, the 65 broom head is inserted in the casing 3 until the bottom of the casing is substantially in alinement with the bottom of the broom. The strings 6 are then tied around the handle of the broom to hold the mop in position. 70 The extension 4 is then placed over the rear side of the casing and the strings 11 and 12 are tied. The extension may readily be detached by untying the bows 13 and the device removed.

75 It is to be understood that the form of the invention herewith shown and described is to be taken as a preferred example of the same, and that various changes in the shape, size, and arrangement of parts may be resorted to without departing from the spirit of the invention or the scope of the subjoined claims.

Having thus described my invention, I 80 claim:

1. A mop attachment for brooms comprising a casing open at each end and adapted to be inserted over a broom, an extension secured to the lower edge of a portion of said casing, said extension being adapted to pass 85 under the broom and extend over the opposite side of the casing, ribbons secured to the upper edge of the casing, and adapted to be tied around the broom handle, means for fastening the free end of said extension to 90 the opposite side of the casing, and mop elements arranged on one side of said casing and on said extension.

2. A mop attachment for brooms comprising a casing open at each end and adapted to 95 be inserted over a broom, an extension secured to the lower edge of a portion of said casing, said extension being adapted to pass under the broom and extend over the opposite side of the casing, ribbons secured to the 100 upper edge of said casing and adapted to be

5 tied around the broom handle, ribbons secured to the free end of said extension, ribbons arranged on said casing to which said ribbons on the extension are adapted to be secured to retain the extension in position, and mop elements secured to one side of said casing and to said extension.

In testimony whereof I affix my signature in presence of two witnesses.

WILLIAM H. GLENN.
